SHOE BAG

Daniel B. Schwartzman, Glen Garden, and William Jindella, North Bergen, N. J., assignors to Protex Company, Jersey City, N. J., a corporation of New Jersey

Application May 15, 1948, Serial No. 27,176

2 Claims. (Cl. 150—1)

1

This invention relates to shoe bags.

An object of this invention is to provide a shoe bag comprising a back sheet of synthetic plastic sheeting, a pocket sheet made of synthetic plastic formed and stitched to the back sheet at its lower edge and at its side edges and intermediate portions of the pocket sheet being fused to the back sheet along parallel spaced lines to form a plurality of pockets open at their upper ends.

Yet a further object of this invention is to provide a shoe bag of the character described, in which each fused area terminates above the bottom stitched edge of the pocket sheet so that the lower ends of the pockets are interconnected by spaces to facilitate cleaning the bottoms of the pockets.

Still another object of this invention is to provide a construction of the character described, in which each fused area comprises an enlarged portion at the top, from which an elongated narrow portion extends and the enlarged portion being curved, thereby making it difficult to tear the pocket sheet away from the back sheet, particularly when strain is exerted on the pocket in a downward direction due to heavy shoes being inserted into the pockets.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown a preferred embodiment of this invention,

Fig. 1 is a front elevational view of a shoe bag embodying the invention;

Fig. 2 is a cross-sectional view taken on line 2—2 of Fig. 1;

Fig. 3 is an enlarged cross-sectional view taken on line 3—3 of Fig. 1;

Fig. 4 is an enlarged cross-sectional view taken on line 4—4 of Fig. 1; and

Fig. 5 is a cross-sectional view taken on line 5—5 of Fig. 1.

Referring now in detail to the drawing, there is shown a shoe bag embodying the invention. The same comprises a back sheet 11 which may be made of synthetic plastic sheeting of thermoplastic type. The sheet 11 is substantially of rectangular shape with rounded corners. Attached to the front of the sheet 11 are a plurality of pocket sheets 12, likewise made of thermoplastic sheeting, similar to the material of which the back sheet 11 is made. The pocket sheets 12 are parallel to each other, and spaced one above the other. The border of the back sheet 11 is covered by binding tape 13, stitched thereto, as at 14. The binding tape 13 is folded over the

edge of the back sheet and the edges of the binding tape are folded inwardly as shown in Fig. 5 of the drawing. The bottom and sides of the lowermost pocket sheet 12, are attached to the back sheet by means of the binding 13 and stitching 14. The sides of the other pocket sheets are attached to the back sheet likewise by said binding 13 and stitching 14. However, the lower ends of the pocket sheets above the bottom one are stitched to the back sheet by means of parallel tapes 16 stitched by lines of stitching 17. Each pocket sheet 12 comprises a plurality of pockets 18 having inwardly pleated portions 19 at opposite sides of each pocket. The lower ends of the inwardly pleated portions 19 of each pocket are stitched in pleated condition either by the stitching 14 at the bottom, or by the transverse lines of stitching 17. The portions 19 are attached to the back sheet by means of fusing parts thereof to the back sheet, as at 20. The fusion may be accomplished either by application of high frequency current or heat, or by use of solvents. Whichever method of fusion is used, there is a fused area between each pair of adjacent pockets 18 for attaching parts of portions 19 between the pockets to the back sheet. Each area 20 has an upper rounded or substantially circular portion 21 located somewhat below the upper edge of sheet 12. Extending downwardly from the enlarged rounded area or portion 21 is a narrow area 22, bisecting the circular portion 21. The portions 22 of the various fused areas 20, are parallel to one another. The fused area 20 terminates well above the lower ends of the pockets. In fact, the fused area may comprise only about $\frac{1}{3}$ of the length or height of each pocket. Thus, the insides of the pocket may communicate with each other at their lower ends. In other words, the lower ends of portion 19 are not fused to the back sheet, but may be separated therefrom, so that a cleaning cloth may be inserted and the bottom of the pockets cleaned readily from one side of the shoe bag to the other. The enlarged rounded area 21 makes it more difficult for the pockets to tear away from the back sheet. When heavy shoes are inserted into the pockets, the pull on the pockets is downwardly, thus the pull would be exerted mainly against the upper ends of the fused areas, and since the upper ends of the fused areas are enlarged and rounded, the chance of tearing is minimized.

Stitched to the upper end of the rear of the back sheet 11 is a transverse strip 30. The strip 30 is stitched at its upper end to the back sheet 11 by means of the binding 13. The ends of the strip 30 are likewise bound to the back sheet by the binding 13. The lower edge of the strip 30 may be stitched to the back sheet by a transverse line of stitching 31.

Thus, between the back sheet 11 and the

strip 30 is formed a chamber 32. Received within the chamber 32 is a metal frame 33 of wire having a top portion 34, a bottom portion 35 and end portions 36. The wire frame is thus rectangular, but may be split. The portions 34 and 35 are fairly close together. The sheet 11 and strip 30 are further interconnected and pressed together by means of a pair of spaced grommets 37 located within the rectangular frame 33. Thus, the grommets 37 may engage hooks on which to hang the shoe bag. A skirted ornamental member 40 may be employed to overlie and hide the grommets. The member 40 is stitched to the upper edge of the backing sheet 11 by the binding 13. Member 40 may comprise a pair of spaced sheets 41 of synthetic plastic sheeting between which is padding 42. The sheets 41 together with the padding 42 may be quilt stitched, as at 44. The member 40 does not extend fully to the sides of the shoe bag and its bottom and side edges may be bound by binding 47.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described our invention, we claim as new and desire to secure by Letters Patent:

1. In combination a backing sheet, a pocket sheet attached to the front of the backing sheet at its sides and bottom edges, portions of the pocket sheet being fused to the backing sheet

along parallel spaced lines forming pockets therebetween, said fused portions terminating short of the bottom edges of the pockets, whereby the bottom edges of the pockets communicate, said backing sheet and pocket sheet being made of flexible thermoplastic material.

2. In combination a backing sheet, a pocket sheet attached to the front of the backing sheet at its sides and bottom edges, portions of the pocket sheet being fused to the backing sheet along parallel spaced lines forming pockets therebetween, said fused portions terminating short of the bottom edges of the pockets, whereby the bottom edges of the pockets communicate, said backing sheet and pocket sheet being made of flexible thermoplastic material, each fused area having a larger upper end and a narrower and longer portion extending downwardly from said enlarged portion.

DANIEL B. SCHWARTZMAN.
WILLIAM JINDELLA.
